UNITED STATES PATENT OFFICE

2,649,411

MERCURY CATHODE ELECTROLYTIC CELL

Harry Shaw, Albert Thompson, and Thomas I. J. Toler, Runcorn, England, assignors to Imperial Chemical Industries Limited, a corporation of Great Britain

Application January 24, 1950, Serial No. 140,228
In Great Britain February 7, 1949

5 Claims. (Cl. 204—219)

1

The present invention relates to new and improved means for the continuous and automatic adjustment of the height of the anodes within electrolytic cells of the flowing mercury cathode type.

In cells using graphite anodes disintegration of the anodes takes place, chiefly at their undersurfaces, as electrolysis proceeds. This disintegration, the causes of which are not clearly understood, makes necessary either periodic or continuous adjustment of the anode height to maintain the size of the interelectrode gap and the efficiency of the cell. Various means have been described for adjusting the anode height in flowing cathode mercury cells, either separately or in association with means for sealing the upper to the lower part of the cell.

In copending application Serial No. 20,564, of G. T. Meiklejohn, now U. S. Patent No. 2,596,583, there is described and claimed an electrolytic cell incorporating an automatic and continuously adjusting assembly in which the graphite anode masses are supported within the cell by means of a series of relatively small bodies resting on the cell bottom and so shaped as to make only linear, i. e., edge surface, contact with the anodes which anodes may be modified to secure the required linear contact and convenient positioning of the supporting bodies. Conveniently the supporting bodies employed in the said adjusting means are in the form of cones, the vertices of which penetrate suitably-shaped cavities in the anode masses. As the electrolytic process proceeds, and disintegration takes place at the lower surface of the anodes, the anodes descend gradually and continuously on the supporting bodies, so that the interelectrode gap remains approximately constant in size and the efficiency of the cell is thus maintained.

The present invention which is an improvement in and modification of the cell and adjusting means described in copending application No. 20,564 of G. T. Meiklejohn, now U. S. Patent No. 2,596,583, and, in particular, relates to a new and convenient means of maintaining the gas-tightness in such cells, while permitting the free downward movement of the anodes under gravity.

We have found that in cells employing the automatic adjusting means above described, the sealing of the cell may be achieved in a surprisingly effective manner by providing a thin sheet of flexible material, resistant or made resistant to the cell gases, wide enough to span the width of the cell and of a convenient length to form the

2

cover thereof, the said thin sheet having holes to fit the supporting rods of the anodes and being provided with sealing means adapted to prevent the escape of gas through the hole and past the anode supporting rod. In an advantageous form of the invention the supporting rods may be machined so that the diameter of the upper portion is less than the lower, thus forming a horizontal shoulder on the supporting rod, the joint between the supporting rods and the flexible sheet being then made by means of a joint-ring of resilient material between the horizontal shoulder thereon and the inside surface of the flexible cover and another similar joint-ring between the outside surface of the flexible sheet and a metal cover-dome over the upper end of the anode supporting rod. Electrical contact with the anode supporting rod may be made by means of a vertical copper conductor fitted into the supporting rod and passing through the metal cover-dome, the whole assembly being maintained tight by means of a nut on the copper conductor, which nut holds down the cover-dome on to the part of the supporting rod external to the cell.

An advantageous form of the invention will now be described with reference to the attached drawing. In the drawing Figure 1 shows a vertical section through a cell constructed according to the invention and Figure 2 is a vertical section showing in detail a suitable means of sealing the anode supporting rods to the flexible cell cover. Figure 3 shows a vertical section through a preferred means of sealing the supporting rod to the cell cover. In the figures similar numbers refer to similar parts. The flexible cover 1 is formed of polymerized methyl methacrylate and is tightly secured to the flange of the lower part of the cell by means of a metal strip 2, which strip is held in position by bolts 3, 3. The anode

4 of the cell has an undersurface substantially parallel to cell base plate 21 and is supported substantially by a series of small conical pegs 5, 5 of insulating material which have stems projecting into cavities 6, 6 in the underface of the anode block. This method of supporting the anode is more fully described in copending application No. 20,564 of G. T. Meiklejohn, now U. S. Patent No. 2,596,583. The upper ends of the anode supporting rods 7, 7 are so machined that they are provided with a horizontal shoulder 8, between which shoulder and the flexible cover 1 there is located a joint-ring 9 made of soft rubber neoprene or other resilient material. Above the flexible cell cover there is located a similar

joint-ring 10 which is held tightly on to the flexible cover by the base-flange of a metal cover-dome 11, which cover-dome is held in position by a nut 12, screwed to a threaded vertical metal spindle 13 which is fixed into the upper part of the anode supporting rod and passes through a hole in the top of the cover-dome. It is found advantageous to corrugate the flexible cover as shown at 14 in both Figures 1 and 2; this has the effect of promoting greater local flexibility in the regions where the anode supporting rods are sealed to the cover. The corrugations run lengthwise either across the entire width of the flexible cell cover or in the region of the holes thereof through which the anode supporting rods pass. The use of the nut 12 for the purpose of securing the electrical conductors to the anodes is envisaged but is not shown in the drawing. In one arrangement of the electrical conductors short leads from the cover-dome nuts are connected to rigid conductors running along the length of the cell and held in position down the cell cover. The cell base plate 21 is substantially horizontal but normally is slightly inclined in order to impart flow to the mercury cathode which it supports. The cell is also provided with side walls 22.

In Figure 3, in which similar numbers refer to similar parts to those shown in Figures 1 and 2, there is shown another preferred means of sealing the anode supporting rod to the flexible cell cover. In this embodiment the resilient joint-ring above the flexible cover is held firmly in position by means of a mild steel ring which is screwed on to a threaded portion 16 of the anode supporting rod. The electrical connection to the anode may conveniently be made by means of a nut 17 fixed to a metal stirrup 18 which is held by nuts 19, 19 at the ends of a rod 20 which passes through the upper part of the anode supporting rod.

With regard to the cell cover, which may be of any suitable flexible and resistant material, it is to be noted that this may be constructed from several flexible sheets, suitably jointed together to maintain the gas-tightness of the cell, polymerised methyl methacrylate being particularly suitable for building up the cell cover in this way, since the individual sheets may be cemented together at their edges by means of cement comprising the monomer containing the polymer in solution.

Since many changes may be made in the details and illustrations set forth above without departing from the spirit and scope of the inven-

tion, it is to be understood that the invention is not limited to such details except as indicated in the appended claims.

We claim:

- 5 1. A flowing mercury cathode electrolytic cell having continuous and automatic adjustment of the height of the anode, comprising in combination a substantially horizontal cell base plate for supporting a flowing mercury cathode, side walls, an anode having an undersurface substantially parallel to said base plate, an array of small supporting bodies resting on the cell base plate supporting the major part of the weight of the anode above said cell base plate, said bodies making edge surface contact only with the said anode, an integral vertically flexible cover on the cell, said cover being substantially uniformly flexible throughout and the edge of said vertically flexible cover being rigidly fixed to the said side walls of the cell, anode supporting rods extending from the upper surface of the anode through holes in said flexible cover and means fixedly sealing said rods to said cover whereby the cover is caused to move with said anode as anode wear takes place.
- 10 2. An electrolytic cell as claimed in claim 1 wherein the flexible cell cover is made of polymerized methyl methacrylate.
- 15 3. An electrolytic cell as claimed in claim 1 wherein the flexible cell cover is made of a thin sheet metal, said metal being protected from the action of electrolytic gases by means of a coating of bituminous paint.
- 20 4. An electrolytic cell as claimed in claim 1 wherein the flexible cell cover is made of polymerized tetrafluoroethylene.
- 25 5. An electrolytic cell as claimed in claim 1, having lengthwise corrugations in the cover at least in the region of the cover through which said anode supporting rods extend.
